UNITED STATES PATENT OFFICE.

ROBERT L. CARLSON AND RAYMOND C. WYMAN, OF BOSTON, MASSACHUSETTS.

PROJECTOR.

1,196,517.

Specification of Letters Patent. Patented Aug. 29, 1916.

Application filed February 4, 1916. Serial No. 76,485.

To all whom it may concern:

Be it known that we, ROBERT L. CARLSON and RAYMOND C. WYMAN, citizens of the United States of America, and residents of 5 Boston, in the county of Suffolk and State of Massachusetts, have invented certain new and useful Improvements in Projectors, of which the following is a specification.

The invention relates to devices for projecting pictures on screens and has for its object the production of a simple and effective apparatus of this character adapted especially to be used for advertising purposes, and for use in motion picture theaters while 15 the motion picture machine is being permitted to cool.

The invention consists primarily of a revoluble drum having two series of lantern slides on its periphery, said drum being 20 adapted to rotate intermittently and during the nonrotating periods to be shifted endwise thereby to cause the various slides in both series to be brought alternately into alignment with the projecting means.

25 The invention further consists in mechanism for extinguishing the lamp during the various movements of said drum.

The invention further consists in a novel means for reciprocating the drum endwise.

30 The invention further consists in certain novel features of construction and arrangement of parts which will be fully understood by reference to the description of the drawings and to the claims hereinafter given.

35 Of the drawings: Figure 1 represents a horizontal section of an apparatus embodying the principles of the present invention. Fig. 2 represents a vertical section of the 40 same, the cutting plane being on line 2—2 on Fig. 1. Fig. 3 represents a horizontal section of the same on line 3—3 on Fig. 2. Fig. 4 represents a horizontal section of the same on line 4—4 on Fig. 2. Fig. 5 represents a vertical section of the same on line 45 5—5 on Fig. 1, and Fig. 6 represents a diagram showing the wiring connecting the various electrical devices thereof.

Similar characters designate like parts 50 throughout the several figures of the drawings.

In the drawings, 10 is a casing having secured to one side thereof a bracket 11 sup-

porting a projecting lens 12 of any well-known construction, the mounting for said lens projecting through the side wall of the casing as indicated in Figs. 1, 2, and 5 of the drawings. To the inner wall of the casing 10 is secured another bracket 13 having mounted therein a second lens 14 in alignment with the lens 12. As the lenses 12 and 14 and the mountings therefor are of any well-known construction, they are not illustrated in detail, but are simply shown in elevation. On the bottom 10^a of the casing 10 are two grooved tracks 15 and 16 in the grooves of which are mounted a plurality of balls or other anti-friction members 17. Supported on the balls 17 is a platform or carriage 18 adapted for movement transversely of the casing 10. Secured to this platform or carriage 18 is a framework 19 consisting of two rectangular side frames connected by a plurality of rods 20. Between the side frames of the framework 19 75 are a plurality of revoluble disks or rollers 21 adapted to rotate freely about the rods 20. Supported by the rollers 21 are two annular members 22 connected together by means of grooved strips 23 and forming a 80 revoluble drum adapted to be rotated about its axis by means to be hereinafter described. The axis of said drum is perpendicular to the optical axis of the lenses 12 and 14. In the grooves of the strips 23 are mounted a 85 plurality of lantern slides 24, said lantern slides being in two series, side by side, each series preferably containing an odd number of slides.

Mounted upon the platform or carriage 18 90 is an electric motor 25 to which current is conducted through the wires 26 connected with the binding posts 27. This motor may be of any well-known construction, and is provided with a revoluble pinion 28 meshing 95 with the gear 29 upon a shaft 30 revoluble in bearings 31 in a bracket 32 secured to said platform or carriage 18. The inner end of the shaft 30 has secured thereto a bevel pinion 33 meshing with a bevel gear 34 secured 100 to and revoluble with a vertical shaft 35 mounted in a bearing formed upon the bracket 32 and having secured to its lower end a lever 36 the outer end of which is provided with an arcuate bearing surface 37. 105 When the motor 25 is in operation the lever

36 is moved in the direction of the arrow *a*. Secured to the bottom 10^a are two obstructions 38^a and 38^b in the path of the arcuate end 37 of the lever 36. The lever 36 moves 5 freely in the direction of the arrow *a* until the end 39 of the arc portion thereof comes into contact with the obstruction 38^a, as indicated in Fig. 3 of the drawings. When the end 39 comes into contact with the obstruction 38^a, further movement of the free end of the lever 36 is prevented, but as the motor 25 continues to operate the lever 36 will be moved about the bearing end 39 as a fulcrum, thus causing the shaft 35 to be 10 moved in the direction of the arrow *b* into the position shown in dotted lines at *c* in Fig. 3 of the drawings. While the arc portion of the lever 36 is moving toward the obstruction 38^a, its curved bearing surface 37 will be in contact with the curved surface 40 of a cam member 41 secured to the bottom 10^a of the casing 10. When the end 39 contacts with the obstruction 38^a the rear end 42 of the arc portion of the lever 36 will 15 reach the highest portion 43 of the cam member 41, and as the shaft 35 begins to move in the direction of the arrow *b* this end 42 will travel along the curved surface 44 of the cam member 41 until the end 39 reaches the 20 curved end 45 of the obstruction 38^a, at which time the lever 36 will again be free to move without obstruction. Before the rear end 42 of the arc portion 37 of the lever 36 is free from contact with the curved surface 45 of 25 the stop member 38^a, the forward portion of said bearing surface 37 will coact with the curved surface 46 of the cam member 47 secured to the bottom 10^a of the casing 10. This bearing surface will then remain in 30 contact with the curved surface 46 until the forward end 39 of the lever 36 contacts with the obstruction 38^b, at which time the rear end 42 will have reached the highest point 48 of the said cam member 47 and the lever 35 will be again rocked about the end 39 as a fulcrum, thus causing the shaft 35 to be moved in a direction opposite to that indicated by the arrow *b* on Fig. 3 of the drawings. During this latter movement the rear 35 end 42 of the arc portion of the lever 36 will travel along the cam surface 49 of said cam member 47 until the end 39 reaches the curved portion 50 of the obstruction 38^b, and then the lever 36 will be free to move about 40 the axis of the shaft 35 until the end 39 thereof again contacts with the obstruction 38^a. By means of this construction the platform or carriage 18 is reciprocated transversely of the casing 10 and remains at a standstill at 45 the end of its movement in either direction. By means of the arcuate bearing surface 37 contacting with the curved cam surfaces 40, 44, 46, and 49, of the cam members 41 and 47, and the curved surfaces 45 and 50 of the 50 obstructions 38^a and 38^b, there can be no lateral movement of the platform 18 when said platform reaches the end of its movement in either direction. This is of considerable importance, for while the platform is at rest it is intended that the picture upon one of the 55 lantern slides 24 should be projected through the lenses 12 and 14 upon a screen of any well-known construction, and obviously it is essential that there should be no slight movement or vibration of the platform while 60 the picture is being projected. To further limit the movement of the carriage 18 in either direction, the bottom 10^a has secured thereto a plurality of blocks or stop members 51 in the path of projections 52 extending 65 downwardly from the bottom of said reciprocating carriage 18. At the opposite ends of the platform 18 are secured downwardly extending plates 53 the inner faces of which 70 contact with the balls or antifriction members 17 and cause them to move along the tracks 15, 16 as the platform 18 reciprocates transversely of the casing 10. The shaft 30 has also secured thereon a bevel gear 54 meshing with a bevel gear 55 secured to a 75 shaft 56 perpendicular to the shaft 30 and revoluble in the bearings in a support 57 secured to the platform 18. The opposite end of the shaft 57 has secured thereto a sprocket wheel 58 from which power is transmitted 80 through an endless sprocket chain 59 to a sprocket wheel 60 mounted upon a shaft 61 revolubly mounted in a support 62 secured to the platform 18. 85 Secured to the inner end of the shaft 61 is a disk 63 having a cam path 64 in the outer face thereof. Pivoted at 65 to the member 62 is a lever 66 having a projection 67 thereon extending into the groove 64. The upper end of the lever 66 is provided 90 with a projection 68 which is adapted when said lever is moved to the right of Fig. 2 to enter the slots 69 between projections 70 extending outwardly from the face of one 95 of the annular members 22. The cam disk 100 63 has projecting from its inner face a pin 71 which as said cam disk 63 revolves enters one of the slots 69 and bearing against a projection 70 moves the drum 22-23 about its axis a predetermined distance. This 110 distance is sufficient to carry the center of one lantern slide 24 out of the optical axis of the lenses 12-14 and the center of a succeeding lantern slide into said optical axis. As the pin 71 leaves the slot 69 the cam 115 throw of the groove 64 will act upon the lever 66 to move the projection 68 into another slot 69 and lock the drum from further rotation until the pin 71 in its movement about the axis of the shaft 61 engages 120 the next succeeding projection 70 when the lever 66 will be moved to the left of Fig. 2 125 of the drawings and permit the rotation of

said drum a predetermined distance by said pin 71. On the end of the lever 66 is a contact member 72 adapted to engage another contact member 63 secured to the frame 19. 5 The contact member 72 is electrically connected to a wire 74 and the contact member 73 is electrically connected to another wire 75.

Within the revoluble drum 22-23 is positioned an electric lamp 76 of high power, this lamp being secured to one wall of the casing 10 by means of a socket 77. From the lamp 76 extends a wire 75 to the contact 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

projected unless the operator opens the 65 switch 82 to stop the motor 25.

The device is particularly adapted for advertising purposes, but may be used in many other ways, as for instance, in motion picture houses where pictures may be 70 thrown upon the screen by means of this projector while the reels in the moving picture apparatus are being changed.

It is believed that the operation and many advantages of the invention will be fully 75 apparent without further description.

Having thus described our invention, we claim:

1. In a device of the class described, the combination of projecting means; a revoluble drum; a plurality of series of lantern slides carried thereby; a lamp within said drum; means for intermittently rotating said drum; and means for moving said drum endwise to bring either series of slides 85 in the plane of said lamp and projecting means.

2. In a device of the class described, the combination of projecting means; a revoluble drum; a plurality of series of lantern 90 slides carried thereby, each series having an odd number of slides therein; a lamp within said drum; means for intermittently rotating said drum; and means for moving said drum endwise to bring alternately 95 either series of slides in the plane of said lamp and projecting means.

3. In a device of the class described, the combination of projecting means; a revoluble drum; a plurality of series of lantern 100 slides carried thereby; a lamp within said drum; means for intermittently rotating said drum; means for moving said drum endwise to bring either series of slides in the plane of said lamp and projecting 105 means; and means for extinguishing said lamp during the end movement of said drum.

4. In a device of the class described, the combination of a revoluble drum; a plurality 110 of series of lantern slides carried thereby; a lamp within said drum; a projecting lens alined with said lamp, a condensing lens within said drum and in alinement with said projecting lens; means for intermittently rotating said drum; and means for moving said drum laterally whereby either series of slides may be brought into the plane of said lamp and lenses.

5. In a device of the class described, the 120 combination of a revoluble drum; a plurality of series of lantern slides carried thereby; a lamp within said drum; a projecting lens alined with said lamp, a condensing lens within said drum and in alinement 125 with said projecting lens; means for intermittently rotating said drum; means for moving said drum laterally whereby either

series of slides may be brought into the plane of said lamp and lenses; and means for extinguishing said lamp during the lateral movements of said drum.

- 5 6. In a device of the class described, the combination of a casing; a lens in the wall thereof; a carriage movable perpendicularly to the axis of said lens; a framework thereon; a drum revolvably mounted in said framework; means thereon for supporting a plurality of lantern slides in two series; a lens within said drum alined with said casing lens; a lamp within said drum; means for rotating said drum intermittently; and means for moving said carriage to bring either series of slides in the plane of said lamp and lenses.
- 10 7. In a device of the class described, the combination of a casing; a lens in the wall thereof; a carriage movable perpendicularly to the axis of said lens; a framework thereon; a drum revolvably mounted in said framework; means thereon for supporting a plurality of lantern slides in two series; a lens within said drum alined with said casing lens; a lamp within said drum; means for rotating said drum intermittently; means for moving said carriage to bring either series of slides in the plane of

- 15 said lamp and lenses; and means for automatically extinguishing said lamp during the movements of said drum.
- 20 8. In a device of the class described, the combination of a casing; a lens in the wall thereof; a carriage movable perpendicularly to the axis of said lens; a framework thereon; a drum revolvably mounted in said framework; means thereon for supporting a plurality of lantern slides in two series; a lens within said drum alined with said casing lens; a lamp within said drum; means for rotating said drum intermittently; means for moving said carriage to bring either series of slides in the plane of
- 25 said lamp and lenses; and means for automatically extinguishing said lamp during the movements of said drum.

- 30 9. In a device of the class described, the combination of a casing; a lens in the wall thereof; a carriage movable perpendicularly to the axis of said lens; a framework thereon; a drum revolvably mounted in said framework; means thereon for supporting a plurality of lantern slides in two series; a lens within said drum alined with said casing lens; a lamp within said drum; means for rotating said drum intermittently; and means for moving said carriage to bring either series of slides alter-
- 35 nately in the plane of said lamp and lenses.

- 40 10. In a device of the class described, the combination of projecting means; a slidable framework; a plurality of rollers thereon; two revoluble annular disks supported by said rollers; strips connecting said disks and adapted to support a plurality of series of lantern slides; a lamp within the path of movement of said slides alined with said projecting means; and means for rotating said disks; and means for moving said framework to bring either series of slides into the line of projection.
- 45 11. In a device of the class described, the combination of projecting means; a slidable framework; a plurality of rollers thereon; two revoluble annular disks supported by said rollers; strips connecting said disks and adapted to support a plurality of series of lantern slides; a lamp within the path of movement of said slides alined with said projecting means; and means for rotating said disks; and means for moving said framework to bring either series of slides into the line of projection.

- 50 12. In a device of the class described, the combination of projecting means; a slidable framework; a plurality of rollers thereon; two revoluble annular disks supported by said rollers; strips connecting said disks and adapted to support a plurality of series of lantern slides; a lamp within the path of

55 movement of said slides and alined with said projecting means; a plurality of spaced projections on one of said disks; a revoluble member; a finger thereon adapted at each revolution of said member to coact with one of said projections and rotate said disk a limited amount; and means for moving said framework to bring either series of slides into the line of projection.

60 13. In a device of the class described, the combination of projecting means; a slidable framework; a plurality of rollers thereon; two revoluble annular disks supported by said rollers; strips connecting said disks and adapted to support a plurality of series of lantern slides; a lamp within the path of movement of said slides and alined with said projecting means; a plurality of spaced projections on one of said disks; a revoluble member; a finger thereon adapted at each revolution of said member to coact with one of said projections and rotate said disk a limited amount; a switch for controlling said lamp operable by said revoluble member; and means for moving said framework to bring either series of slides into the line of projection.

65 14. In a device of the class described, the combination of projecting means; a platform movable relatively thereto; a revoluble lantern-slide-carrying drum mounted thereon and movable therewith; a fixed lamp within said drum alined with said projecting means; a revoluble shaft extending through said platform; means for rotating said shaft; a lever on the lower end of said shaft; and fixed obstructions in the path of the outer end of said lever.

70 15. In a device of the class described, the combination of projecting means; a platform movable relatively thereto; a revoluble lantern-slide-carrying drum mounted thereon and movable therewith; a fixed lamp within said drum alined with said projecting means; a revoluble shaft extending through said platform; means for rotating said shaft; a lever on the lower end of said shaft; fixed obstructions in the path of the outer end of said lever; and means for limiting the reciprocatory movement of said platform.

75 16. In a device of the class described, the combination of projecting means; a platform movable relatively thereto; a revoluble lantern-slide-carrying drum mounted thereon and movable therewith; a fixed lamp within said drum alined with said projecting means; a revoluble shaft extending through said platform; means for rotating said shaft; a lever on the lower end of said shaft; fixed obstructions in the path of the outer end of said lever; a plurality of fixed stops; and projections on the under side of said platform adapted to engage said stops

and limit the movement of said platform in either direction.

15. In a device of the class described, the combination of projecting means; a platform movable relatively thereto; a revolute lantern-slide-carrying drum mounted thereon and movable therewith; a fixed lamp within said drum alined with said projecting means; a revolute shaft extending through said platform; means for rotating said shaft; a lever on the lower end of said shaft having an arcuate bearing surface at its outer end; fixed obstructions in the path of the outer end of said lever; and fixed members having cam surfaces adapted to coact with said bearing surfaces when said lever is in engagement with said fixed obstructions.

16. In a device of the class described, the combination of projecting means; a platform movable relatively thereto; a revolute lantern-slide-carrying drum mounted thereon and movable therewith; a fixed lamp within said drum alined with said projecting means; a revolute shaft extending through said platform; means for rotating said shaft; a lever on the lower end of said shaft; and means disconnected from said lever but coacting therewith to impart reciprocatory movement to said platform during the rotation of said shaft.

17. In a device of the class described, the combination of projecting means; a platform movable relatively thereto; a revolute lantern-slide-carrying drum mounted thereon and movable therewith; a fixed lamp within said drum alined with said projecting means; a revolute shaft extending through said platform; means for rotating said shaft mounted on said platform; a lever on the lower end of said shaft; and means disconnected from said lever but coacting therewith to impart reciprocatory movement to said platform during the rotation of said shaft.

18. In a device of the class described, the combination of projecting means; a platform movable relatively thereto; a revolute lantern-slide-carrying drum mounted thereon and movable therewith; a fixed lamp within said drum alined with said projecting means; a revolute shaft extending through said platform; means for rotating said shaft; a lever on the lower end of said shaft; and means disconnected from said lever but coacting therewith to impart reciprocatory movement to said platform during the rotation of said shaft; and means connected with said shaft-rotating-means for intermittently revolving said drum.

19. In a device of the class described, the combination of projecting means; a platform movable relatively thereto; a revolute lantern-slide-carrying drum mounted there-

on and movable therewith; a fixed lamp 65 within said drum alined with said projecting means; means for reciprocating said platform including a motor mounted upon said platform; a plurality of spaced projections on said drum; and a revolute member 70 provided with a lateral pin adapted to engage said projections successively during the rotation of said member.

20. In a device of the class described, the combination of projecting means; a platform movable relatively thereto; a revolute lantern-slide-carrying drum mounted thereon and movable therewith; a fixed lamp within said drum alined with said projecting means; means for reciprocating said platform including a motor mounted upon said platform; a plurality of spaced projections on said drum; a revolute member provided with a lateral pin adapted to engage said projections successively during the rotation 80 of said member; and means driven by said motor for rotating said revolute member.

21. In a device of the class described, the combination of projecting means; a platform movable relatively thereto; a revolute 90 lantern-slide-carrying drum mounted thereon and movable therewith; a fixed lamp within said drum alined with said projecting means; means for reciprocating said platform including a motor mounted upon said platform; a plurality of spaced projections on said drum; a revolute member provided with a lateral pin adapted to engage said projections successively during the rotation 95 of said member and having a cam surface thereon; a pivoted lever contacting with said cam surface and movable thereby about its pivot; and a switch for controlling said lamp actuated by the movements of said lever.

22. In a device of the class described, the combination of projecting means; a platform movable relatively thereto; a revolute lantern-slide-carrying drum mounted thereon and movable therewith; a fixed lamp 110 within said drum alined with said projecting means; means for reciprocating said platform including a motor mounted upon said platform; a plurality of spaced projections on said drum; a revolute member provided with a lateral pin adapted to engage said projections successively during the rotation 115 of said member and having a cam groove therein; a pivoted lever having a projecting stud in said groove and movable thereby about its pivot; and a switch for controlling said lamp actuated by the movements of said lever.

23. In a device of the class described, the combination of projecting means; a platform movable relatively thereto; a revolute lantern-slide-carrying drum mounted thereon and movable therewith; a fixed lamp

within said drum alined with said projecting means; means for reciprocating said platform including a motor mounted upon said platform; a plurality of spaced projections on said drum; a revoluble member provided with a lateral pin adapted to engage said projections successively during the rotation of said member; and means controlled by said revoluble member for restraining said drum from rotary movement 10 at predetermined times.
